COMBINED COASTER AND HOLDER
FOR A BEVERAGE CANEdward J. Paprocki, 86—48 Sancho St.,
Hollis, N.Y. 11423Original design application July 19, 1966, Ser. No. 3,127.
Divided and this application May 16, 1967, Ser. No.
7,150

Term of Patent 14 years

(Cl. D44—21)

FIG.1

FIG.3

FIG. 1 is a side elevational view of a combined coaster and holder for a beverage can showing my new design;
FIG. 2 is a front elevational view;

FIG. 3 is a fragmentary sectional view taken along lines 3—3 of FIG. 1.

This is a division of my earlier filed application, Ser. No. D. 3,127 of July 19, 1966, now abandoned.

I claim:

The ornamental design for a combined coaster and holder for a beverage can, as shown and described.
